UNITED STATES PATENT OFFICE.

JOSEPH A. JEFFREY, OF COLUMBUS, OHIO.

CONVEYER.

SPECIFICATION forming part of Letters Patent No. 340,321, dated April 20, 1886.

Application filed June 19, 1885. Serial No. 169,200. (No model.)

To all whom it may concern:

Be it known that I, JOSEPH A. JEFFREY, a citizen of the United States, residing at Columbus, in the county of Franklin and State 5 of Ohio, have invented certain new and useful Improvements in Conveyers, of which the following is a specification, reference being had therein to the accompanying drawings.

Figure 1 is a side view, partly in section, 10 illustrating my invention. Fig. 1^a is a similar view, some of the parts being omitted, and showing a slightly different construction. Fig. 2 is a side elevation of the chain, taken from the side opposite from that shown in 15 Fig. 1. Fig. 3 is a side elevation of the chain with the links in such position that the parts may be detached from each other. Figs. 4, 5, 6, 7, 8, 9, 10, and 13 are details. Fig. 11 is a transverse section of the chain on line *xx*, 20 Fig. 2. Fig. 12 is a transverse section on line *yy*, Fig. 3. Fig. 14 is a plan or top view of Fig. 1, part of the trough sections being removed to show the chain. Fig. 15 is a detached view of the trough section or conveyer- 25 section in perspective and enlarged. Fig. 16 shows a modification of the trough-section and means for supporting the upper loaded line of the chain. Fig. 17 is a plan view of a modi- 30 fication. Fig. 18 is a plan view showing the modified form of rollers used for supporting the lower line of the chain.

The object of my invention is to construct a practically endless conveyer mounted upon and carried by a driving-chain, or two or 35 more driving-chains arranged in parallel lines; and to this end one part of the invention consists, essentially, in the combination of a driving-chain and a series of open-ended carrier-sections arranged in close proximity to each 40 other, as will be hereinafter fully explained.

The invention further consists in certain details of construction and combination.

Similar letters of reference indicate like parts in all the figures.

I will first describe the construction of a 45 detachable chain having anti-friction rollers applied thereto, which I propose to use for the more perfect carrying out of my invention, and will afterward describe the conveyer- 50 trough sections and some modified forms of the invention.

I will first describe in detail the construc-

tion of the separate parts, and afterward explain their relation to each other when united to form a chain and placed in different relative positions.

Referring to the drawings, A B C is one of the side bars, the part B being expanded and provided with a circular opening to receive the pintle.

b is a notch or recess at one side of the pintle-seat.

The parts A and B are in different planes, so as to leave a shoulder at *a*. The part C is also expanded and provided with a tubular 65 extension or sleeve, D, which receives the pintle and also forms a bearing for an anti-friction roller, to be hereinafter referred to. The part C is of less thickness than the intermediate part, A, so that there is a shoulder 70 at *c*.

All of the side bars upon one side of the chain are duplicates of each other. The side bars upon the opposite side of the chain are also duplicates of each other, and are con- 75 structed as follows:

E is the intermediate portion, provided with two gripping or clasping ears, *ee*. The part F is expanded and provided with a circular seat to receive the pintle, and is of less thickness than the intermediate part, E, so that there is a shoulder at *f*. The part G is also expanded in diameter and provided with a tubular extension or sleeve, D, which forms a seat to receive the pintle and also fits within 85 the anti-friction roller.

I' is a keeper-plate, the part I' of which is provided with an oblong or rectangular central slot. The shank portion I of this keeper is firmly attached to the intermediate part, 90 E, of the side bar, preferably by means of the gripping or grasping ears *ee*, in such position that its opening shall be substantially opposite to the pintle-seat, which is formed in or constituted by the tubular extension D'D of 95 the adjacent links.

In practice I propose to cast the ears *ee* upon the intermediate part, E, and projecting at right angles therefrom, as shown at the right-hand end of Figs. 1 and 3, so as to facilitate drawing the pattern from the sand; and as these side bars are usually made of malleable iron, the ears can be bent down upon the shank I of the keeper after the latter has been placed

in proper position, as is indicated at the center of Figs. 1 and 3 and at the right-hand end of Figs. 7 and 8; but I do not wish to be limited to either of these modes of attaching the keeper to the side bar, because it might be done in many other ways. For instance, the keeper might have a circular or angular hole in it, as indicated in dotted lines, Fig. 13, the side bar being cast with a corresponding lug, 5 which might be riveted down after the keeper is placed in position; or the lugs might be cast with grooves in their inner faces to receive the edges of the shank of the keeper, the inner end of which might be upset after insertion, so as to hold it firmly in place; or other modified constructions might be employed to hold the keeper in place.

By preference, I construct the keeper with an offset or shoulder at I', so as to increase 20 the width of the throat or space between the enlarged end I' and the adjacent face of the part C of the side bar.

K L M is the pintle, the part K being circular in cross-section, except as hereinafter 25 noted. The part K is of such diameter as to fit closely within the seats formed for the reception in the tubular extensions D D and in the adjacent ends of the next pair of side bars, and is provided at one end with a lug or spur, 30 k, which enters the notch b, so as to prevent the pintle from turning round relative to the ends of the side bars.

M is a flat head. At its opposite end the pintle is reduced in diameter and provided 35 with a locking-plate, L, which is oblong or rectangular in shape, its width being about equal to the diameter of the reduced portion or shank of the pintle, its longer diameter being about equal to the greater diameter of the 40 part K of the pintle, thus leaving a throat, l, which is adapted to receive the keeper, as will be explained.

By an examination of the drawings it will be readily understood that when the side bars 45 are in the position shown in Fig. 3 the pintle can be thrust through them, and also through the keeper of it, the pintle being held in such position that the lug k will enter the notch b; and it will be understood that if, after the 50 pintle has thus been thrust into place, the links be straightened out, the pintle will be turned a quarter of the way round by reason of the engagement of the lug with the notch. Thus the locking-plate L will be turned cross- 55 wise of the opening I in the keeper, so that it (the pintle) cannot be withdrawn from the side bars. Therefore the parts of the chain will be held firmly in proper working position, except when moved into the unusual relative 60 position shown in Fig. 3.

H H are anti-friction rollers mounted upon the sleeves or tubular extensions; but I do not wish to be limited to the employment of these rollers, because under many circumstances the 65 chain will operate satisfactorily without them. By reason of the parts C, F, and G being thin-

ner than the intermediate parts, A E, respectively, of the links the outer edges of the chain are in substantially parallel planes, thus constituting what is commonly known as a "ribbon" chain. 70

While in ordinary practice I prefer to make this chain of malleable iron, yet I do not wish to be limited thereby, as it may be made of any suitable material. 75

I am aware that chains have heretofore been made with shoulders in many respects like those at a f, which subserved a useful purpose in preventing the links from moving transversely to the pintles when the links were in 80 ordinary working position, the construction of these earlier chains being such, however, that said movements of the links relative to the pintles was requisite when connecting or disconnecting the members of the chain; nor do 85 I wish to be limited to making the side bars with the tubular extensions upon which the anti-friction rollers are mounted, because they might be omitted, in which latter case the anti-friction rollers might be mounted directly upon 90 the pintle, though I prefer the construction shown, because these tubular extensions increase the durability of the chain by furnishing a greater extent of wearing-surface to bear upon the pintles. It will also be seen that the 95 space between the keeper and the end G of the link constitutes a throat for the reception of one end of the adjacent side bar.

I will now describe the construction of the carrier-sections and the wheels adapted to 100 support and actuate them, together with the chain.

N is a sprocket-wheel provided with a series of projecting teeth, n, adapted to engage 105 with the centrally open links of a driving-chain, which, by preference, is provided with a series of anti-friction rollers surrounding the pintles or end bars which unite adjacent links of the chain, as has been fully explained.

O O' O' O' is one of the open-ended carrier-sections or trough-sections. Each of the ends O' projects beyond the end of the bottom section, and the part o' is beveled off or rounded, for a purpose which will soon be explained. The bottom O' is made, by preference, a 115 little longer than the distance between the centers of the end bars of the links to which the carrier-sections are attached. According to one plan the middle portion of the bottom of each section is sunken or depressed some distance below the ends, as at o', for a purpose 120 which will soon be explained. I propose to make these conveyer-sections of sheet metal, striking them up or swaging them into proper form, either by hand or by use of proper machinery; or they may be made of cast metal, 125 preferably of malleable iron. They should be rigidly attached to the chain-links by rivets, screws, or similar appliances, and in practice I propose to cast the links with upward and laterally projecting ears or wings P p, through 130 which rivets may pass into and through the

bottoms of the conveyer sections; or the side bars of the links or the laterally-projecting ears may have upwardly-projecting spurs adapted to pass through holes in the middle portions of the bottom O^2 , and then be riveted down.

As indicated in Figs. 1 and 2, these carrier sections are secured upon the links in such positions that one end of the bottom of each section overlaps slightly the adjacent end of the next section in the series, which overlapped end is arranged about on a line with the center of the end bar or of the pintle or pivot immediately below it, the opposite end of the bottom projecting slightly beyond the center of the pivot of the forward end of the same link. (See Fig. 1.) The ends $O' O'$ of the sides of the trough-section overlap the ends of the sides of the adjacent trough-section, thus insuring a practically continuous and unbroken trough or conveyer when the chain and conveyer are passed around the sprocket-wheel; but this overlapping need not be of the extent shown in the drawings, although I prefer to so construct them that the ends of two adjacent sections shall not be separated when passing around the wheel, in order to insure that they shall overlap when straightening out without the ends abutting against each other. I prefer that the rear overlapping end of each trough-section shall be arranged on about a line with the center of the end bar or pintle immediately below it, the opposite end of the same bottom projecting slightly beyond the center of the pivot of the forward end of the same link. (See Fig. 1.)

The object in beveling off or rounding the portions $o' o'$ of the sides of the conveyer-section is to prevent the corners $e' e'$ from projecting above the sides e when passing around the sprocket-wheels.

Although I propose under some circumstances to employ two lines of chain as a support for the conveyer, I do not wish to be limited thereby, because under many circumstances a single line of chain can be used advantageously, the bottom of such carrier-section being attached to the side bars of each link of the chain or of each alternate link of the chain. Nor do I wish to be limited to the employment of a drive-chain having centrally-open links, because the trough-sections might be applied to any suitable chain adapted to traverse grooved wheels; or the sections might be connected to a rope or belt under such construction and arrangement of parts as to form a practically continuous conveyer.

I have shown each of these sections constructed with central transverse partitions, o^2 , which is desirable whenever it is necessary to incline the chain at very much of an angle, in order to prevent the material from slipping backward in a trough; but under many circumstances, particularly when the conveyer is to run in a nearly horizontal position, these partitions may be omitted, because the con-

veyer will then generally operate satisfactorily without them.

Although I have shown in Fig. 1 each conveyer-section about equal in length to two of the chain-links, each section being attached near one end to one of the links, yet I do not wish to be limited thereby, as under some circumstances the sections may about equal in length the links, as shown in Figs. 1^a and 2, 75 wherein each section is attached near its center to the center of one of the links.

Under some circumstances I propose to employ two supporting ribs or ways—one arranged upon each side of the trough-conveyer—80 to be traversed by the lugs or arms which project on either side of each of the trough-sections, and I also propose to employ supporting-rollers $R R$, to be traversed by the under line or empty line of trough-sections, 85 which are in an inverted position, and, when preferred, these latter referred to supporting-rollers may be made of such width as to enter between the sides of the trough-sections and engage with the bottoms O^2 . 90

As a modification, the trough sections may have parallel sides, the alternate sections being wide enough to receive the ends of the intermediate sections, as indicated in Figs. 16, 17, and 18, although, under ordinary circumstances, I prefer to make each section with converging sides, so that one end of each section shall receive the end of the section immediately in advance. It will of course be understood that the ways or tracks N are to be 100 firmly supported so that they shall support the weight of the upper line of conveyer without undue deflection. 95

I am aware that it is old to construct elevators of a series of separate and independent 105 buckets mounted upon and carried by a drive-chain composed of separate detachable links, and hence I do not claim as my invention elevators of this class; but the conveyer herein described differs very materially from such 110 earlier forms of elevators, in that, instead of a series of separate elevator-buckets, each complete in itself and adapted to elevate material in a vertical or nearly vertical line, I employ a series of carrier-sections adapted to lie contiguous and together form an endless conveyer adapted to convey material in a horizontal or nearly horizontal line. 115

I am aware that overlapping carrier-sections or pans having bottoms and upwardly-projecting sides are old, and that such sections have been connected to form an endless carrier or conveyer by means of eyes riveted to the under sides of the bottoms of the sections and rods passing through said eyes. These rods 125 have been extended outwardly beyond the sides of the carrier-sections, and have had mounted thereon supporting-rollers adapted to travel upon rails or guides situated at the sides of the carrier, and the carrier has been 130 driven by means of a spider-wheel having fingers provided with semicircular ends, which

engage with the projecting ends of the connecting-rods outside of the carrier-sections.

I am also aware that overlapping carrier-sections or pans have been supported upon 5 two parallel lines of chains, such chains being united together by means of cross-shafts at the joints of the links of the chains, thus forming an endless carrier, and that a carrier of this description has been driven by a wheel 10 engaging with said cross-shafts between the parallel lines of chains.

I am also aware that carrier-sections or pans have been attached to single-bar links connected together by rivets or riveted pintles to 15 form a non-detachable chain, such links being provided with lateral projections which engage with a driving-wheel; but my device differs in many respects very materially from such earlier constructions. In the first place, I employ 20 for supporting the carrier-section a separable drive-chain—that is, a chain adapted to drive or to be driven by a sprocket or other wheel, the links or component parts of which chain are separable from each other, in order 25 that the length of the carrier may be changed without necessitating the mutilation or destruction of any of the parts. In the second place, my device differs from such earlier constructions in providing the link which supports 30 the carrier-section with an anti-friction roller, for the purposes which have been described. Besides these differences, there exist many others, which will be hereinafter pointed out in the claims.

35 What I claim is—

1. In an endless conveyer, a drive-chain composed of separable links and connecting end bars, in combination with separable carrier-sections, each having a bottom plate and 40 upwardly-projecting sides, and means, substantially as described, for attaching the carrier-sections to the chain-links, substantially as set forth.

2. In an endless conveyer, a supporting and 45 driving chain having separable links and end bars, in combination with separable carrier-sections, the bottom of each section having a length greater than the distance between the centers of the end bars of each link, the forward end of each bottom plate overlapping 50 the rear end of the adjacent section, substantially as set forth.

3. In an endless conveyer, the combination, with an endless chain, of carrier-sections provided 55 with lateral projections adapted to traverse a support arranged on a line parallel with the bottom of the conveyer, substantially as set forth.

4. In a conveyer, the combination, with a 60 series of open-ended carrier-sections, of the chain-links provided with anti-friction rollers and a supporting-track traversed by the rollers, substantially as set forth.

5. In a conveyer, a series of open-ended carrier-sections, in combination with a series of 65 chain-links having anti-friction rollers ar-

ranged below the carrier-sections, substantially as set forth.

6. In a conveyer, the combination of an open-ended carrier-section with a chain-link 70 having separable side bars and an anti-friction roller supported upon the end bars, substantially as set forth.

7. In a conveyer, a carrier-section having a portion of its bottom projecting downward 75 below another portion of its bottom, in combination with a chain-link having an anti-friction roller mounted thereon, substantially as set forth.

8. In a conveyer, the combination of a carrier-section with a chain-link having an anti-friction roller mounted thereon, and having also its side bars expanded and projecting above the plane of the anti-friction roller, to receive the carrier-section, substantially as set 85 forth.

9. In an endless conveyer, the combination of a series of overlapping carrier-sections having lateral projections and supports arranged on lines parallel with the bottoms of the carrier-sections and engaging with the lateral 90 projections, substantially as set forth.

10. The herein-described conveyer-section, having a bottom, upward-projecting sides, and a transverse partition arranged intermediately 95 between its ends, substantially as set forth.

11. The combination, with an endless chain and carrier-sections mounted thereon so as to form a practically continuous conveyer, of driving and supporting wheels at the ends of 100 the chain and intermediate supporting-rollers arranged between the ends of the chain and below the lower line thereof and engaging with the carrier-sections, substantially as set forth.

12. The combination, with the drive-chain and the carrier-section, of the supporting and driving wheels at the ends of the doubled chain and the intermediate supporting-wheels arranged to enter between the sides of the carrier and engage with the bottom of the carrier, substantially as set forth.

13. In an endless conveyer, carrier-sections each having its bottom recessed upon its upper surface at one end and recessed upon its 115 lower surface at the opposite end, substantially as set forth.

14. In a conveyer, the combination of parallel lines of supporting and driving chains and a series of thin metal carrier-sections 120 each attached at each of its ends to a single link of the chain, and having one edge underlying an adjacent carrier-section, and having also its opposite edge overlapping an adjacent carrier-section, substantially as set 125 forth.

15. In a conveyer, the combination of parallel lines of chains having centrally-open links adapted to receive the spurs of sprocket-wheels, in combination with a series of overlapping carrier-sections attached at their ends 130 to the chains, substantially as set forth.

16. The herein described carrier-section, having a thin metal supporting-plate attached at its ends to links of chains, the links being adapted to be coupled or uncoupled from similar links when the carrier-sections are placed at about a right angle to each other, substantially as set forth.

17. In an endless conveyer, the combination of a series of carrier-sections mounted on an endless chain, supports upon each section ar-

ranged entirely outside the edges of the section, and supports below the conveyer for the returning lower line of the conveyer, substantially as set forth.

In testimony whereof I affix my signature in presence of two witnesses.

JOSEPH A. JEFFREY.
